[57] CLAIM

The ornamental design for a loose fill packing element, as shown and described.

DESCRIPTION

FIG. 1 is a top plan view of a loose fill packing element according to my invention;

FIG. 2 is an end view thereof, the opposite end being a mirror image of the end shown;

FIG. 3 is a bottom plan view thereof;

FIG. 4 is a side elevational view thereof, the side not shown being a mirror image of the side shown; and,

FIG. 5 is a sectional view taken as line 5—5 in FIG. 1.
